RADIAL PUMP

Rudolph W. Glasner, Chicago, and Einar K. Johansen, Oak Park, Ill., assignors, by mesne assignments, to Midwest Hydraulics, Inc., Chicago, Ill., a corporation of Illinois

Application February 4, 1943, Serial No. 474,658

10 Claims. (Cl. 103—174)

This invention relates to variable displacement multi-plunger type pumps or motors in which the cylinders in which the pistons reciprocate are stationary, and the means which actuate the pistons in one direction are rotatable, and one of the objects of the invention is to simplify and improve the construction and arrangement, and to reduce to a minimum the heavy rotating mass in pumps of this general character.

A further object is to reduce the size of such pumps and to permit the pump to be operated at a high rate of speed, at the same time maintaining a high capacity, and improved means for varying or adjusting the capacity or volumetric discharge of the pump.

A further object is to provide a pump of this character in which the pistons will be moved in one direction by positive means, and in the opposite direction by fluid pressure, means being provided whereby the piston positive actuating means may be readily adjusted at will to vary the volumetric discharge of the pump.

A further object is to provide in a pump of this character, improved means whereby the fluid will be delivered into the cylinders through a hollow rotating shaft, which fluid, due to the centrifugal action of the shaft, will be forced into the suction line leading to the pump cylinders.

The passage through which the fluid flows into the cylinders serves both as an inlet and a discharge outlet for the respective cylinders, the final discharge of the fluid being controlled by a rotating valve mechanism.

The arrangement of the valve and pump is such that very large suction openings and large overlap will be produced, thereby increasing the efficiency and ease of operation of the pump. Furthermore, the number of rotating parts is reduced to a minimum, and such parts are located in close proximity to the center of rotation, the pump and its parts all being lubricated by the incoming fluid which is being circulated by the pump.

To the attainment of these ends and the accomplishment of other new and useful objects as will appear, the invention consists in the features of novelty in substantially the construction, combination and arrangement of the several parts, hereinafter more fully described and claimed and shown in the accompanying drawings illustrating this invention, and in which

Fig. 1 is a vertical longitudinal sectional view of a pump constructed in accordance with the principles of this invention.

Fig. 2 is a sectional view taken on line 2—2, Fig. 1.

Fig. 3 is a left-hand end elevation of Fig. 1.

Fig. 4 is a detail horizontal sectional view taken on line 4—4, Fig. 3.

Fig. 5 is a detail view, partly in elevation and partly in section, taken on line 5—5, Fig. 3.

Fig. 6 is a detail sectional view taken on line 6—6, Fig. 5.

Figs. 7, 8, 9 and 10 are sectional views taken on line 7—7, Fig. 1, showing the valve element in various positions.

Referring more particularly to the drawings, there is shown a pump embodying a casing 15, having a cover member 16 removably secured thereto by means of fastening bolts 17. In the casing there is provided a plurality of radially arranged bores or cylinders 18 encompassing a central opening 19. These cylinders are arranged in a common plane and are preferably spaced at equal distances from each other, any number of cylinders being employed, and the number may be varied in accordance with the pumping characteristics desired.

Each of the cylinders 18 is closed at its outer end in any suitable manner, preferably by means of a plug or member 20 having an extension 21 which projects into the cylinder for any desired distance, the member 21 being preferably reduced at its end 22 to form a chamber 23.

The casing 15 is provided, adjacent each of the cylinders, with a chamber 26, each of the cylinders having communication with the respective chambers 26 by means of lateral openings 25 in the respective members 21.

Arranged in each of the cylinders is a piston member 27, which is provided with a reduced end 28 that has a bearing in the member 21 and projects into a chamber 24.

The casing 15 is provided, at the inner end of each of the cylinders 18, with an enlarged portion 29 preferably provided with a straight wall 30, and slidable within this portion 29 is a member or cross-head 31 which is angular in cross-section and engages the walls 30 so as to maintain the member 31 against axial rotation.

Carried by the member 31 and journaled upon a suitable shaft 32 is a roller 33 having a ball or roller bearing 34, and the member 31 is separate from the piston 27, but contacts the end of the piston to positively move the latter in one direction.

Passing through the casing 15 is a shaft 35, which is supported by means of sleeves 36—37 secured thereto for rotation therewith, and interposed between the sleeve 36 and the wall of an opening in the cover member 16, through which

the sleeve passes, are roller bearings 38. Similar roller bearings 39 are disposed between the sleeve 37 and the wall 40 of an opening in the casing 15. These roller bearings 38-39 are disposed in close proximity to the plane of rotation of an eccentric member 41, which latter encompasses the shaft 35 and is secured thereto for rotation therewith by means of cam or wedge-shaped members 43-44, which latter pass through the eccentric 41 and are respectively movable in guides or ways 45-46 in the shaft 35.

Encompassing the eccentric 41 is an annular member 47, ball or roller bearings 48 being disposed between the periphery of the eccentric 41 and the inner surface of the annular member 47. The eccentric 41, together with the annular member 47, is held against displacement in directions lengthwise of the axis 35 by means of portions 49 on the sleeves 36-37, and these sleeves are of such an internal diameter as to permit the cam or wedge-shaped members 43-44 to be moved in directions lengthwise of the shaft 35.

It will therefore be manifest that as the eccentric is secured to the shaft 35, it will be rotated by the rotation of the shaft 35, and as the annular member 47 engages the roller 33 on the members 31, which latter engage the pistons 27, the pistons will be moved positively by the eccentric in one direction. The extent of movement of the pistons 27 by the eccentric is controlled by the position of the eccentric with respect to the shaft 35. That is, by adjusting the eccentric in directions transverse to the axis of the shaft 35, the extent of movement of the pistons 27 will be varied, with the result that the volumetric discharge of the pump will also be varied.

Any suitable means may be provided for adjusting the cam or wedge-shaped members 43-44. It will be noted that these members taper in opposite directions, and may be of any desired configuration to rest upon or extend about the shaft 35.

A suitable and efficient means for adjusting the eccentric comprises a sleeve 50 which is rotatable with the shaft 35. This sleeve 50 is provided with a recess 51, into which a shoulder or projection 52 on each of the members 43-44 projects, and the sleeve 50 is disposed within another sleeve 53, which latter has threaded engagement 54 into a tubular member 55, the latter being secured to the cover member 16 by means of fastening bolts 56.

Disposed within the sleeve 53, and intermediate the sleeve 50 and the inner face of the sleeve 53, are ball bearings 57, a collar 58 being provided to maintain these parts in relative position.

A cap member 59 is secured in position by means of a fastening pin or bolt 60. It will be manifest that by rotating the cap member 59 in any suitable manner, such as by means of an implement inserted into one or more openings 61 in the cap member, and as the member 59 is secured to the sleeve 53, which latter has threaded engagement with the tubular member 55, the sleeve 50 will be moved in one direction or the other, according to the direction of rotation of the sleeve 50. This will move the cam or wedge-shaped members 43-44 in directions lengthwise of the shaft 35 and through the eccentric 41, thereby causing the eccentric 41 to be adjusted in directions transverse to the axis 35, according to the direction of rotation of the sleeve 53. Such adjustment may be accomplished while the shaft 35 is rotating, if desired. Therefore, by adjusting the sleeve 53, the volumetric discharge of the pump may be varied, because such adjustment will determine the po-

sition of the eccentric 41 with respect to the shaft 35, and therefore the extent of movement of the respective pistons 27 in one direction.

Within the wall of the casing 15 a plurality of passages 62 are provided, one of these passages leading to each of the cylinders 18 and communicating with the respective chambers 23, to serve as both an inlet and a discharge outlet for the fluid. When the piston 27 is moved in one direction, that is, in a direction toward the shaft 35, a suction will be created in these passages 62 and fluid will be drawn into the cylinders 18 through the chambers 23, but when the piston is moved in the opposite direction by the eccentric, the fluid will be discharged through the same passages 62.

Fluid is supplied to the cylinders through the shaft 35, a portion of which shaft is tubular, as at 63, and the shaft is provided with a lateral opening 64 that is adapted to be brought into communication with the passages 62, and moved out of communication therewith, during the rotation of the shaft. To accomplish this, there is provided a tubular valve member 65 which encompasses the tubular end of the shaft. This valve member is provided with a passage way 66 that has communication with the passage 64 and is movable into and out of communication, respectively, with the passages 62.

The valve member 65 is also provided with another passage way 67 which has communication with an annular passage way 68 in a sleeve 69 that encompasses the valve member 65 and has a bearing in the opening 40 in the wall of the casing 15.

The passage way 68 has communication with a discharge outlet 70 for the fluid. Thus, when the shaft 35 is rotated, and with it the valve member 65, the passage 66 is successively brought into communication with the passages 62 so as to deliver fluid into the respective cylinders. Upon further rotation of the valve member, the passage way 67, through the medium of passages 71 and 71a, is successively brought into communication with the passage 62, thereby permitting the fluid to be discharged from the pump by the piston 27, to be delivered through the discharge outlet 70.

By referring to Figures 7 to 10, it will be noted that the passage way 64 is brought into communication with certain of the passage ways 62, while others of the passage ways 62 are brought into communication with the discharge outlet passage 67, and as the valve member rotates, fluid will be successively drawn into the cylinders, and subsequently the fluid will be successively discharged from the cylinders through the passages 62, through the outlet passage 70.

The valve member 65 is held in position by means of a collar 72, and, if desired, roller bearings 73 may be mounted upon the end of the shaft 35 and held in position by means of an adjustable sleeve or member 74 that, in turn, is secured by means of a fastening member 75 to the tubular member or sleeve 69. This member, in turn, is held against rotation by means of suitable fastening screws 76.

A cap member 77 may be provided for the end of the casing 15, and is shaped to form a chamber 78, within which chamber is arranged a gear 79 that is secured to the shaft 35 for rotation therewith, and through the medium of which gear member the shaft is rotated.

The pistons 27 are moved in the opposite direction, that is, in a direction opposed to the direction of movement thereof by the eccentric, by

fluid pressure which may be derived from any suitable source, such as from a pump 18 which may be of any desired or suitable construction. Suffice it to say that the pump is operated in any suitable manner, and is provided with an inlet opening 19 and a discharge outlet opening 80, so that fluid will be delivered from the pump through the outlet 80 under pressure, so as to flow through a pipe or passage way 81, to be delivered to an annular chamber 82 in the pump casing, and an annular plate 82^a, and from the chamber 82 through passage ways 83, into the chambers 26, through the passages 25, so as to operate upon the end of the portion 28 of the respective pistons, thereby moving the respective pistons 27 in the opposite direction, or in a direction to create suction and draw fluid into the cylinders, by the action of the fluid discharged from the pump 18.

It will therefore be manifest that, inasmuch as the annular chamber 82 is in communication with the respective passages 83 (see Fig. 1) of the different cylinders, there will be a constant pressure exerted upon the pistons, tending to move them in a direction towards the shaft 35. However, as the eccentric will resist such movement of the pistons, the pressure of the fluid against the end of the pistons will cause the pistons to remain in contact with the eccentric, and as soon as the eccentric has assumed a proper position, the pistons will be moved inwardly and will always remain in contact with the eccentric through the intermediate members. This movement of the pistons under the fluid pressure causes the fluid to be drawn into the cylinders, to be discharged therefrom by the pistons when the pistons are moved in the opposite direction by the eccentric.

If desired, a fluid pressure relief valve 84 may be arranged within the fluid pressure line 81. This valve may be of any desired construction, and may be set through the medium of a spring, or other means, to control the valve 84, to be operated at a predetermined pressure.

Connected to the shaft 87 of the pump, is a gear wheel 88 which meshes with the gear 79 that is carried by the shaft 35, as shown more clearly in Fig. 4, so that upon operation of the pump 18 the shaft 35 will be rotated, and with it the eccentric 41, together with the valve member 65.

It is thought that the operation of the pump will be clearly understood from the foregoing, but, briefly stated, it is as follows:

The eccentric 41 is adjusted to the desired position, according to the volumetric discharge that is desired, by the adjustment of the cam or wedge-shaped members 43—44, by sliding them longitudinally of the shaft 35. When the pump 18 is operated, fluid pressure will be created thereby, which will be manifested through the pipe 81 against the ends of the pistons 27, tending to force the pistons inwardly towards the shaft, and holding the ends thereof in contact with the members 31 which, in turn, engage the annular member 47 carried by the eccentric 41.

As the shaft 35 rotates, the valve member 65 will also rotate, and according to the position of the passage 66 in the valve member with respect to certain of the passages 82, the latter will receive a supply of fluid through the shaft 63, as shown more clearly in Figures 7 to 10, while the passage 67 will be in position with respect to others of the passages 82. In this position of the parts, fluid will be forced by centrifugal action through the hollow shaft 63 into certain

passages 62 through the passages 64—66 (see also Fig. 1), while the pistons 27 are being moved under the influence of the fluid pressure from the pump 18, and at the same time the passage 67 of the valve member will assume a position with others of the passages 62 so as to receive a discharge of fluid from the passages 62, to be delivered to the outlet 70. Thus, it will be seen that as the shaft 35 and eccentric 41 rotate, the passages 62 will successively and alternately deliver fluid to the cylinders 18, and will receive the discharge of fluid from the cylinders 18, according to the direction of movement of the pistons 27. By adjusting the position of the eccentric 41 in the manner heretofore described, the volumetric discharge of the pump may be varied.

Suitable lubrication passages similar to the passage 65^a for the bearings, may be provided wherever necessary or desirable, and oil overflowing the wall or baffle 89 will find its way through a suitable drain opening, to be delivered to a tank, or conveyed away.

With this improved construction, it will be seen that the number of rotating parts in a pump of this character has been materially reduced, and the shaft 35 is supported in close proximity to the eccentric 41 near the center of rotation. Lubricating fluid will flow within the casing, and will accumulate within the space 19 to lubricate the parts, and a constant level of lubricant will be maintained within the casing through the medium of the wall 89, shown more clearly in Fig. 1 of the drawings.

The present construction also permits of the use of very large suction openings and also large overlap on the valve member, increasing the efficiency of the pump and the ease of operation. Furthermore, the pistons are separate from the members which are disposed between the pistons and the eccentric, and the auxiliary pump forces the pistons toward the eccentric to cause them to always contact the intermediate member while the latter is held in contact with the eccentric. This is a manufacturing expedient and permits the pistons to be readily removable, independently of the cross-head of the said intermediate members.

While the preferred form of the invention has been herein shown and described, it is to be understood that various changes may be made in the details of construction and in the combination and arrangement of the several parts, within the scope of the claims, without departing from the spirit of this invention.

What is claimed as new is:

1. A pump or motor having a series of radially arranged cylinders, pistons reciprocable therein, a combined fluid inlet and outlet passage in communication with each cylinder at one end thereof, a rotatable shaft adjacent the other ends of the cylinders and provided with a fluid passage, means for rotating the shaft, means carried by the shaft for positively moving the pistons in one direction, means whereby fluid pressure will operate to move the pistons in the opposite direction, means rotatable with the shaft and disposed between the shaft and one end of the first said passages for alternately establishing and interrupting communication between the passage in said shaft and the adjacent end of the first said passages, and means slidable through the second recited means for adjusting the latter to vary the volumetric discharge of said pump.

2. A pump or motor having a series of radially arranged stationary cylinders, pistons reciprocable therein, a combined fluid inlet and outlet passage in communication with each of the cylinders at one end thereof, a rotatable shaft adjacent the other ends of the passages and through which shaft fluid is supplied to the cylinders by suction created in the cylinders, means carried by the shaft for moving the pistons in one direction, means slidable through the last said means for adjusting the piston moving means with respect to the shaft to vary the volumetric discharge of the pump, a pump, means whereby the last said pump will supply fluid under pressure to move the pistons in the opposite direction, valve means rotatable with the shaft for controlling the entrance and exit of fluid into and out of said cylinders, and an operative connection between said pump and said shaft for rotating the latter.

3. A pump or motor having a series of radially arranged stationary cylinders, pistons reciprocable therein, a combined fluid inlet and outlet in communication with each of the cylinders at one end thereof, a rotatable shaft adjacent the other ends of the said passages and through which shaft fluid is supplied to the cylinders by suction created in the cylinders, means carried by the shaft for moving the pistons in one direction, means for adjusting the last said means with respect to the shaft to vary the volumetric discharge of the pump, a pump for supplying fluid under pressure to move the pistons in the opposite direction, valve means rotatable with the shaft for controlling the entrance and exit of fluid into and out of said cylinders, and an operative connection between said pump and said shaft for rotating the latter, the said connection embodying a gear carried by said shaft, with which a gear on the said pump meshes.

4. A pump or motor having a series of radially arranged stationary cylinders, pistons reciprocable therein, a combined inlet and outlet passage in communication with each of said cylinders, a rotatable shaft adjacent the other ends of said passages and through which shaft fluid is supplied to the cylinders, valve means rotatable with the shaft for controlling said passages, an eccentric carried by the shaft for engaging and moving the pistons in one direction, roller bearings adjacent said eccentric and on opposite sides thereof to support said shaft, means to supply fluid to the cylinders to move said pistons in the opposite direction, means for rotating said shaft, and means movable through said eccentric for adjusting the eccentric with respect to said shaft in a direction transverse to the axis of the shaft to vary the volumetric discharge of the pump.

5. A pump or motor having a series of radially arranged stationary cylinders, pistons reciprocable therein, a head separate from and disposed adjacent one end of and engaging each of the pistons, each of said heads being angular in cross-section and slidable in guide ways, a roller supported by each of the heads, a combined inlet and outlet passage in communication with each of the cylinders, a rotatable shaft adjacent one end of said passages, an eccentric carried by said shaft, separate from, and engaging the rollers on the said heads to respectively move the pistons in one direction, means whereby fluid pressure

will operate to move the pistons in the opposite direction, a rotatable shaft adjacent one end of said passages and through which shaft fluid is supplied to said passages, valve means between the shaft and the adjacent ends of the passages for controlling the latter and rotatable with the shaft, and means for rotating the shaft.

6. A pump or motor having a series of radially arranged stationary cylinders, pistons reciprocable therein, a head contacted by each of the pistons, said head being angular in cross-section and slidable in guide ways, a combined inlet and outlet passage in communication with each of the cylinders, a rotatable shaft adjacent one end of said passages, an eccentric carried by said shaft, separate from, and engaging the said heads to respectively move the pistons in one direction, a separate source of supply of fluid for moving the pistons in the opposite direction and for maintaining the said piston heads in contact with said eccentric.

7. In a pump or motor, a plurality of radially arranged cylinders, pistons reciprocable therein, a rotatable shaft, an eccentric carried by the shaft, cross-heads, rollers carried by the cross-heads, said cross-heads being individual to the pistons, separate therefrom and disposed between the eccentric and the respective pistons and engaged by the pistons and the said eccentric, for moving the pistons separately and in one direction, and means for moving the pistons in the opposite direction and for maintaining the pistons, the rollers on said cross-heads and said eccentric in contact with each other.

8. In a pump or motor, a plurality of radially arranged cylinders, pistons reciprocable therein, a rotatable shaft, an eccentric carried by the shaft, cross-heads individual to the pistons, separate therefrom and disposed between the eccentric and the respective pistons and engaged by both, for moving the pistons separately and in one direction, means for moving the pistons in the opposite direction and for maintaining the pistons, cross-heads and eccentric in contact with each other, said cross-heads being angular in cross-section, and guide-ways for the cross-heads.

9. A pump or motor embodying a plurality of radially arranged cylinders, pistons reciprocable therein, a rotatable shaft, means carried by the shaft and operating on one end of the pistons to move them in one direction, said pistons being separate from said means, the other end of said pistons being reduced to form an elongated stem, and guiding means within and stationary with respect to the cylinders and in which guiding means the stems slide.

10. A pump or motor embodying a plurality of radially arranged cylinders, pistons reciprocable therein, a rotatable shaft, means carried by the shaft and operating on one end of the pistons to move them in one direction, said pistons being separate from said means, the other end of said pistons being reduced to form an elongated stem, and rigid guiding means within and stationary with respect to the cylinders and in which guiding means the stems slide, said pistons each having an open end, upon which open end the said piston moving means operates.

RUDOLPH W. GLASNER.
EINAR K. JOHANSEN.
